UNITED STATES PATENT OFFICE.

EVERETT B. CUSHMAN AND LESLIE S. CUSHMAN, OF LINCOLN, NEBRASKA.

GAS-ENGINE.

SPECIFICATION forming part of Letters Patent No. 703,695, dated July 1, 1902.

Application filed October 25, 1901. Serial No. 79,971. (No model.)

To all whom it may concern:

Be it known that we, EVERETT B. CUSHMAN and LESLIE S. CUSHMAN, citizens of the United States, residing at Lincoln, in the 5 county of Lancaster and State of Nebraska, have invented a new and useful Gas-Engine, of which the following is a specification.

This invention relates to certain improvements in two-cycle gas-engines, and is particularly designed for use in connection with a bicycle or for other light work, although some of the features of the invention may be utilized to advantage in gas-engines of any size.

15 The principal object of the invention is to provide a light and compact engine of simple and economical construction.

A further object is to so construct the engine as to permit of ready access to the inlet 20 and escape ports for cleaning and repairs.

With these and other objects in view the invention consists in the novel construction and combination of parts hereinafter described, and illustrated in the accompanying 25 drawings, and particularly pointed out in the appended claims.

In the drawings, Figure 1 is a transverse sectional elevation on the line 1 1 of Fig. 2, illustrating a gas-engine constructed and arranged in accordance with the invention. Fig. 2 is a sectional elevation of the same on the line 2 2 of Fig. 1. Fig. 3 is a sectional plan view of the engine on the line 3 3 of Fig. 2. Fig. 4 is a view of a portion of the mechanism illustrated in Fig. 2, showing the clutching-hub in elevation. Fig. 5 is an elevation of a portion of the inlet-valve-operating mechanism.

Similar numerals of reference are employed 40 to designate corresponding parts throughout the various figures of the drawings.

5 designates an air-cooled cylinder having the usual radiating ribs 6 and provided with a removable head 7, carrying a plug 8 for the 45 support of the usual sparking terminals of an igniting-circuit.

The cylinder 5 is formed integral with a crank-case 9, substantially circular in form and provided with a removable side plate 10 50 and a removable end plate 11. On one side of the cylinder is placed an oil-cup to supply

lubricant to the piston. The excess of oil accumulates on the crank-chamber and lubricates the crank-pin. The crank-casing and its cover-plate 10 are provided with bearings 55 12 for the reception and support of a crank-shaft 13. The crank-shaft is connected by a rod 14 to a piston 15 of the usual trunk type, adapted to reciprocate in the cylinder, and the upper end of said piston is provided with 60 a gas-deflector 16, as is usual in engines of this class. The packing-rings 15' of the piston are much wider than the gas entrance and escape ports in order to prevent catching in the ports during the reciprocations of the 65 piston.

In opposite sides of the cylinder are entrance and escape ports 17 and 18, respectively, and on the exterior of the cylinder are ribs or flanges 19, arranged one above and one 70 below the said ports. The peripheries of the ribs or flanges 19 are cut away or rabbeted, as at 20, for the reception of a two-part ring 21, the adjacent edges of the sections of the ring being provided with laterally-projecting 75 lugs 22, through which may pass securing bolts or screws 23. The periphery of the cylinder is further provided with radially-arranged ribs 24, arranged between the adjacent ends of the entrance and escape ports and between 80 the upper and lower flanges or ribs 20. These ribs 24 divide the annular space between the cylinder and the ring 21 into two chambers, one of which has an outlet-port 25 for the products of combustion and the opposite chamber 85 being connected to a gas-inlet pipe 26. This chamber is further connected by a vertically-disposed port 27 with the interior of the crank-casing, said crank-casing forming a compression-chamber for compressing the gases 90 before their entrance into the explosion-chamber.

At the mouth of the inlet-pipe 26 is a valve-seat 28 for a valve 29, the stem 30 of which passes through a suitable guide 31 and is provided at or near its outer end with an enlarged head or collar 32, between which and the adjacent end of the guide 31 is placed a compression-spring 33. In a chamber 34 is situated a valve-operating arm 35, said arm 100 being carried on a short shaft 36, adapted to a suitable bearing 37, the opposite end of said

shaft being connected by a rocker-arm 38 and pitman 39 to a crank-pin 40 on a crank-disk 41, carried by the crank-shaft 13.

In the operation of the engine the rotations 5 of the crank-shaft will be imparted through the crank-disk 41 to the valve-operating arm 35, causing the opening of said valve for the admission of the gas during the upward movement of the piston. On the downward movement 10 of the piston under the impulse of an explosion the gases within the crank-chamber will be compressed, and when the piston has reached its lowest point and has opened the inlet-port 17 the gases will rush into and fill 15 the explosion-chamber. The upward movement of the piston will further compress the gases within the explosion-chamber, the explosion being timed to take place at about the time the piston has completed its upward 20 movement.

By removing the screws 23 the sectional ring 21 may be taken from the cylinder for the purpose of cleaning or repairs to the valve or to remove any deposits of carbon from the 25 ports 17 18.

On one end of the crank-shaft is secured the hub 43 of a fly-wheel 44, the web of said wheel having an inset portion for the reception of a grooved belt-wheel 45, over which 30 may pass a suitable belt to transmit the power to the driving-wheel of the bicycle or such other point as may be desired. The belt-wheel is cup-shaped in form and is mounted loosely on the shaft 13, the belt-wheel being 35 provided with locking-pins 46, adapted to suitable openings 47 in the fly-wheel and serving as a means of locking the two together when it is desired to rotate the belt-wheel. On the bearing or hub of the crank-shaft casing 40 is mounted a loose collar 49, provided with an operating-handle 50, extending to any suitable point, and in the periphery of said collar is formed an inclined slot 51, through which passes a pin 52, secured to the hub or 45 bearing of the crank-casing. The outer end of the collar 49 is provided with a peripheral flange 53, adapted to annular slots formed in the pins 46.

In operating the clutch mechanism the 50 handle 50 is turned and causes an inward or an outward movement of the collar 49, the locking-pin being either withdrawn from the openings in the fly-wheel to unlock the belt-wheel or being forced into said openings to 55 lock the fly-wheel in operative position. It will be noted that the clutching-sleeve lies wholly within the cup-shaped belt-wheel, the latter forming a housing or casing to protect the clutch from dirt and dust.

60 While the construction herein described and illustrated is the preferred form of the device, it is obvious that many changes may be made in the form, proportions, size, and

minor details of construction without departing from the spirit or sacrificing any of the 65 advantages of this invention.

Having thus described our invention, what we claim is—

1. The combination, in a two-cycle gas-engine, of a ported cylinder having outwardly-extending flanges at points above and below the cylinder-ports, a removable ring carried by said flanges, partitions dividing the space between the flanges and ring into a plurality of chambers, and gas inlet and escape ports 75 for said chambers, substantially as specified.

2. The combination, in a two-cycle gas-engine, of a cylinder having ports and provided with upper and lower flanges, a ring adapted to said flanges, radial ribs formed on the cylinder between said flanges and serving to divide the annular space within the ring into a plurality of chambers, and gas inlet and escape ports for said chambers, substantially as described. 85

3. The combination, in a two-cycle gas-engine, of a cylinder having ports, upper and lower ribs formed on the cylinder and having peripheral rabbets, a two-part ring mounted in said rabbets, ribs for dividing the space 90 within the ring and flanges into a plurality of chambers, and gas inlet and escape ports for said chambers, substantially as specified.

4. The combination, in a two-cycle gas-engine, of a ported cylinder, a crank-casing, annular flanges formed on the periphery of said cylinder at points above and below the cylinder-ports, one of said flanges being provided with an opening or port for communication with a gas-passage leading between the crank-casing and the cylinder-ports, a sectional ring mounted on said flanges, and gas entrance and escape ports formed in said ring, substantially as specified. 95

5. The combination in a gas-engine of a cylinder, a crank-casing forming a compression-chamber for the explosive mixture, annular flanges formed on the periphery of the cylinder, a ring mounted on said flanges, ribs for dividing the space within the flanges and 100 ring into a plurality of chambers, piston-controlled ports extending between such chambers and the cylinder, an auxiliary port formed in the wall of the cylinder and leading between the crank-casing and one of said 105 chambers, and a valved supply-port in communication with the chamber to which said auxiliary port is connected.

In testimony that we claim the foregoing as our own we have hereto affixed our signatures in the presence of two witnesses. 110
